UNITED STATES PATENT OFFICE.

EPHRAIM SCUDDER AND CLARENCE M. CORLEW, OF SIOUX FALLS, SOUTH DAKOTA,
ASSIGNORS OF ONE-THIRD TO JERRY CARLETON, OF SIOUX FALLS, SOUTH DAKOTA.

HOSE-SUPPORTER.

1,132,395.

Specification of Letters Patent. Patented Mar. 16, 1915.

Application filed October 3, 1914. Serial No. 864,769.

To all whom it may concern:

Be it known that we, EPHRAIM SCUDDER and CLARENCE M. CORLEW, citizens of the United States, and residents of Sioux Falls, 5 in the county of Minnehaha and State of South Dakota, have invented a new and useful Improvement in Hose-Supporters, of which the following is a specification.

Our invention is an improvement in hose supporters, and has for its object to provide a supporter of the character specified, arranged to connect the hose to the under-garments without encircling the leg to cause injurious pressure, and which may be easily 10 attached and detached without any danger of tearing or otherwise injuring the clothing.

In the drawings:—Figure 1 is a front view of the supporter in use, Fig. 2 is an enlarged front view, Fig. 3 is an edge view, 20 and Fig. 4 is a detail view of the clasp proper.

The present embodiment of the invention as shown in Fig. 1 connects the sock 1 with the under-clothing 2 at one side of the leg. 25 The supporter comprises a plurality of resilient clasps, and the connecting element for connecting the clasps. Each clasp is approximately triangular, and is formed from a single piece of resilient wire bent to shape. 30 The clasp proper, that is, that portion of each clasp which grasps the clothing, consists of two members 1, lying alongside each other, the members being connected by a ring or eye 2 to provide a sufficient amount 35 of resiliency to cause the bars to firmly grip a portion of a garment.

As before mentioned, the clasp is formed from wire which may be first bent to form the eye or loop 2, and then to form the gripping jaws or members 1. The ends of the wire are then bent outward in opposite directions and in alinement to form members or bars 3 at right angles to the gripping jaws 1. The ends of the wire are then bent 40 backwardly on the outer side of the members 1, as indicated at 4, to a connection, and the extremities of the wire may be soldered or otherwise connected at the junction of the members or portions 4. Thus each clasp 45 consists of a substantially triangular frame, namely, the members 3 and 4, and a clasp, namely, the members 1 and 2, lying within the frame.

The members 3 of each clasp are connected 50 by strips 5 of fabric material, and the said

strips are preferably of elastic material, although it is obvious that they may be of non-elastic material. The free end of each of the strips 5 is bent around the adjacent bar or member 3, as indicated at 6, and connected to the body of the strip, by stitching 60 7 or the like. The strips 5 are spaced apart at their adjacent edges, as shown, and the said spacing apart is for a purpose that will hereinafter appear. 85

In use, the improved supporter is arranged as shown in Fig. 1. A portion of the material of the sock is engaged between the jaws 1 of the clasp proper, merely by drawing the fold 8 of the sock between the gripping jaws. 70 A portion of the underwear is engaged with the gripping jaws of the other clasp in precisely the same manner, that is, by drawing a small fold 9 of the material of the under-garment between the gripping jaws. 75

It will be noticed that the lower portion of the clasp adjacent to the jaws 1, has an offset or bevel 10, which answers the double purpose of guiding the material into the jaws and the said offsets or bevels also assist in properly spacing apart the strips 5 so that the supporter when in use lies flat against the leg without crowding, or crimping the material in the jaws. With two connecting strips, elastic or otherwise, pulling equally 80 on each side, it is evident that it would be practically impossible for the material to slip through the jaws when in use for the reason that the stronger the pull on the strips the closer the jaws are brought together and the firmer their hold on the material held. There is no impediment to the circulation of the limb with the improved supporter, since it does not encircle the leg; there is no injurious strain on the underwear since the strips 5 yield to compensate 85 for changes in position. 90

The insertion of the eye or loop 2 between the gripping jaws 1 permits them to yield to a greater extent and more freely than would be possible were the said jaws or members parallel throughout their length. It is obvious that the clasps might be formed in other ways than as described. The ends of the wire from which the clasp is formed 105 might be at any portion of the clasp.

The improved supporter is easily attached and detached, the detaching being merely a reversal of the process of attaching. To release the supporter it is necessary to remove 110

one of the folds from between the gripping jaws and the support may be left in place on either the sock or the underwear.

We claim:

- 5 1. A hose supporter, comprising a pair of clasps, each clasp consisting of a piece of resilient wire bent to form a substantially triangular frame, and a clasp proper within the frame, said clasp being formed by a re-entrant portion of one of the sides of the frame, said reentrant portion consisting of gripping jaws lying alongside each other and approximately perpendicular to the side of the frame with which they are connected,
- 10 15 the wire at the connected ends of the said jaws being bent to form an open loop or eye, said clasps being arranged with the sides having the reentrant portions adjacent, and strips of elastic fabric material connect-
ing the said sides one on each side of the re-entrant portion.
- 20 2. A hose supporter, comprising a pair of clasps and a plurality of elastic strips connecting the clasps, each clasp consisting of an open frame of resilient wire, the adjacent sides of the frames having reentrant portions lying within the frames, and each reentrant portion comprising two members or gripping jaws lying alongside each other and connected at the ends remote from the side to which they are connected, said con-

nexion being a loop or eye and the elastic strips being arranged at each side of the gripping jaws.

3. A hose supporter, comprising a pair of 35 clasps, and a flexible connection between the clasps, each clasp consisting of an open frame of resilient wire, the adjacent sides of the frames having reentrant portions lying within the frame, and each reentrant portion comprising two members or gripping jaws lying alongside each other and connected at the ends remote from the sides to which they are connected.

4. A hose supporter, comprising a pair of 45 clasps, and a flexible connection between the clasps, each clasp consisting of an open frame of resilient wire, the adjacent sides of the frames having reentrant portions lying within the frame, and each reentrant portion 50 comprising two members or gripping jaws lying alongside each other and connected at the ends remote from the sides to which they are connected, the said flexible connection comprising flexible strips of equal length ar- 55 ranged alongside each other and spaced apart.
